Primary Examiner — Robert M Spear*Assistant Examiner* — Eliza Bennett-Hattan(74) Attorney, Agent, or Firm — Griffiths & Seaton PLLC;
JoAnn M. Seaton(57) CLAIM

The ornamental design for a wall bracket, as shown and described.

DESCRIPTION

FIG. 1 is a front, perspective view of a wall bracket showing our new design;

FIG. 2 is a front view thereof;

FIG. 3 is a rear view thereof;

FIG. 4 is a right side view thereof, the left side view being a mirror image of the right side view; and,

FIG. 5 is a top view thereof, the bottom view being a mirror image of the top view.

The features shown in broken lines are portions of the wall bracket forming no part of the claimed design.

1 Claim, 3 Drawing Sheets(56)
